DRILLING APPARATUS

Mervin Chester Huffman, Claremont, N. H., assignor to Sullivan Machinery Company, a corporation of Massachusetts

Application June 1, 1934, Serial No. 728,581

15 Claims. (Cl. 121—7)

This invention relates to rock drills, and more particularly to improvements in the rotation control means of such drills.

An object of this invention is to provide an improved rotation control means for a rock drill. Another object is to provide an improved drill steel rotation mechanism for a rock drill and having embodied therein improved release means for such mechanism. A further object is to provide in a rock drill of the hammer piston type improved drill steel rotation mechanism of the intermittent ratchet and pawl type operated by the hammer piston of the drill and having embodied therein improved release means for the drill mechanism whereby, when desired, rotation of the drill steel may be discontinued while the hammer piston continues to operate. These and other objects and advantages will, however, subsequently more fully appear.

In the accompanying drawing there is shown for purposes of illustration one form which the invention may assume in practice.

In this drawing:—

Fig. 1 is a side elevational view of a stoper rock drill having embodied therein the illustrative form of the improved rotation control means.

Fig. 2 is an enlarged longitudinal sectional view taken on line 2—2 of Fig. 1.

Fig. 3 is a cross sectional view taken on line 3—3 of Fig. 2.

Fig. 4 is a fragmentary view taken in the plane of Fig. 2 showing the rotation control parts in a different position.

Fig. 5 is a cross sectional view taken on line 5—5 of Fig. 2.

In this illustrative embodiment of the invention, the improved rotation release mechanism is incorporated in a rock drill of the stoper type of a well known design, generally comprising a hammer motor, generally designated 1, and having a cylinder 2 within which a hammer piston 3 is mounted for reciprocation. This hammer piston is provided in the usual manner with a forwardly projecting striking bar 4 adapted to strike against the shank of a drill steel 5 loosely mounted in the usual manner within a chuck mechanism housed within a front chuck housing 6 attached to the front end of the motor cylinder. The hammer motor is supported by a suitable feed leg 7 comprising a feed cylinder 8 attached to the rear end of the hammer motor and containing a usual feed piston having its feed piston rod 9 terminating in an abutment engaging point 10. The hammer motor is supported and fed by means of this feed leg and is held in position by a usual sup-

porting handle 11 extending laterally from the drill. The grasping portion of this supporting handle may be grasped by the operator to support the drill and hold the drill against rotation about its longitudinal axis in a manner well understood in the art. Fluid under pressure is supplied to the hammer motor 1 and the feed leg 7 through usual supply passages under the control of a usual throttle valve 12 having an operating handle 13.

The rotation mechanism for effecting rotation of the drill steel 5 as it is percussively actuated by the piston 3, is herein of a well known construction and comprises an oscillatory pawl carrier 15 carrying usual spring pressed pawls 16 engageable with the teeth 17 of a ratchet ring 18. This ratchet is herein arranged within a rear head member 19 interposed between the rear motor head and feed leg and is herein guided for movement axially of the drill in a bore 20 formed in the head member 19. Formed integral with the pawl carrier and extending forwardly within the hammer piston is a rifle bar 21 having spiral grooves engageable with spiral lugs formed on a rifle nut 22 secured within the rear end of the hammer piston as shown in Fig. 2. The ratchet ring is held against rotation by means of lug-like projections or keys 23 formed on its periphery and engaging longitudinal grooves or key-ways 24 formed by projections from the walls of the bore 20 within which the ratchet ring is axially guided. As the hammer piston moves forwardly, the pawls 16 slip over the teeth of the ratchet ring to permit unimpeded forward movement of the hammer piston to effect its working stroke, and upon reverse movement of the hammer piston the pawls engage the ratchet teeth, thereby holding the bar 21 against rotation, and as a result causing rotative movement of the hammer piston. This rotative movement of the hammer piston is transmitted to the drill steel 40 chuck mechanism through straight grooves 25 formed on the piston striking bar 4 and engaging straight lugs formed within the usual chuck nut of the chuck mechanism. As the particular drill motor construction and steel rotation mechanism are of a standard design, and as the particular fluid supply means for the motor and feed leg are well known and do not specifically enter into the invention, further description of the same is considered unnecessary. For details of the motor of this type reference may be had, if desired, to the patent to Gartin No. 1,929,420 granted October 10, 1933.

Now referring to the improved rotation release mechanism, it will be noted that the ratchet ring 55

18 is provided with an integral piston 30 on the exterior periphery of the ratchet ring and slidably guided in the bore 20 in the head 19. Also formed integral with the ratchet ring 18 is an 5 annular extension 31 slidably guided in a bore 32 formed in an annular member 33 interposed between the head 19 and the feed leg, and this extension has an inwardly directed annular flange 34 providing an interior cam surface 35. 10 The throttle valve 12 is provided with a port 36 communicable with a passage 37 communicating with a chamber 38, while formed in the rear motor head is a chamber 39 communicating through a passage 40 with the fluid distributing 15 means of the hammer motor. Communicating with the bore 20 at the rear side of the piston 30 is a passage 41 communicable through a groove 42 formed on the throttle valve with a vent passage 43. When the ratchet ring and piston are 20 in the position shown in Fig. 4, the pawls 16 engage the teeth 17 of the ratchet ring and the rotation mechanism operates in a normal manner. If it is desired to release the mechanism, for instance when the drill steel sticks or during 25 spotting of a hole, this may be accomplished by rotating the throttle valve 12 to the position shown in Fig. 2, thereby supplying live pressure fluid through the passage 41 to the rear pressure area on the piston 30. The pressure fluid flowing 30 from the chamber 39 to the motor distribution means causes the pressure fluid in chamber 39 to assume a pressure substantially lower than in the chamber 38, and as a result the pressure acting on the rear pressure area of the piston 30 and on the rear pressure area on the projection 31 causes the ratchet ring to be shifted 35 axially from the position shown in Fig. 4 to the position shown in Fig. 2. As the ratchet ring moves axially inwardly, the cam surface 35 on 40 the flange 34 engages the lower edges of the pawls 16 throwing the latter inwardly into their released position out of engagement with the ratchet teeth of the ratchet ring. It will thus be seen that the pawls at that time are entirely 45 released from the ratchet ring and that the pawl carrier is at that time free to oscillate, and as a result the rotation of the drill steel is interrupted. When the throttle valve 12 is rotated to the position 50 shown in Fig. 4, the pressure area on the rear side of the piston 30 is connected to exhaust, and as a result the pressure in chamber 39 acting on the inner pressure area of the ratchet ring causes the latter to move inwardly 55 to its normal position as shown in Fig. 4, and as a result rotation of the drill steel is resumed. 60 As a result of this invention it will be noted that there is provided an extremely simple and convenient mechanism for controlling the rotation of the drill steel of a rock drill, it being possible entirely to interrupt rotation at will. It will further be noted that the mechanism is free from any complicated operating or adjusting mechanism and that by the mere manipulation of the throttle valve the desired control 65 may be readily effected. These and other advantages of the invention will be clearly apparent to those skilled in the art.

70 While there is in this application specifically described one form which the invention may assume in practice, it will be understood that this form of the same is shown for purposes of illustration and that the invention may be 75 modified and embodied in various other forms

without departing from its spirit or the scope of the appended claims.

What I claim as new and desire to secure by Letters Patent is:

1. In a rock drill, drill steel rotation mechanism including relatively rotatable ratchet and pawl carrier elements, operative connections between one of the same and a drill steel to be rotated, means for holding the other element against rotation, means for moving said latter element axially, and means movable axially with said latter element to effect engagement and release of the pawls of the pawl carrier element from the ratchet. 10

2. In a rock drill, drill steel rotation mechanism including relatively rotatable ratchet and pawl carrier elements, operative connections between one of the same and a drill steel to be rotated, means for holding the other element against rotation, means actuated by fluid pressure for moving said latter element axially, and means movable axially with said latter element to effect engagement and release of the pawls of said pawl carrier element from the ratchet. 15

20 3. In a rock drill, drill steel rotation mechanism including relatively rotatable ratchet and pawl carrier elements, operative connections between one of the same and a drill steel to be rotated, means for holding the other element against rotation, means actuated by fluid pressure for moving the latter element axially, and pawl engaging and releasing means movable axially with said latter element into pawl engaging and releasing position, said latter element being moved in the opposite direction in 25 to its rotation effecting position also by means of fluid pressure. 30

35 4. In a rock drill, drill steel rotation mechanism including an oscillatory pawl carrier and a cooperating ratchet ring, keys on said ratchet ring engageable with keyways on the drill to hold said ratchet ring against rotation, means for effecting axial movement of said ratchet ring, and pawl release means movable axially with 40 said ratchet ring to effect release of the pawls from the ratchet teeth while said keys remain in interlocking engagement with said keyways. 45

50 5. In a rock drill, drill steel rotation mechanism including an oscillatory pawl carrier and a cooperating ratchet ring, keys on said ratchet ring engageable with keyways on the drill to hold said ratchet ring against rotation, means for effecting axial movement of said ratchet ring, pawl engaging and releasing means movable axially with said ratchet ring into pawl engaging 55 and releasing position to release entirely the pawls from the teeth of said ratchet ring while said keys remain in interlocking engagement with said keyways, and means for actuating said ratchet ring moving means in one direction by 60 fluid pressure.

6. In a rock drill, drill steel rotation mechanism including an oscillatory pawl carrier and a cooperating ratchet ring, keys on said ratchet ring cooperating with keyways on the drill to hold said ratchet ring against rotation, means for effecting axial movement of said ratchet ring, pawl engaging and releasing means movable axially with said ratchet ring into pawl engaging 65 and releasing position to release entirely the pawls from the teeth of said ratchet ring, and means for actuating said ratchet ring moving means in either direction by fluid pressure. 70

7. In a rock drill, drill steel rotation mechanism including an oscillatory pawl carrier and a co- 75

- operating ratchet ring, keys on said ratchet ring engageable with keyways on the drill to hold said ratchet ring against rotation, means for guiding said ratchet ring for axial movement, pawl engaging and releasing means movable axially with said ratchet ring into pawl engaging and releasing position to release entirely the pawls from the teeth of said ratchet ring, and means for actuating said ratchet ring in one direction by fluid pressure, including a piston secured to said ratchet ring and means for supplying fluid pressure to act on said piston. 5
8. In a rock drill, drill steel rotation mechanism including an oscillatory pawl carrier and a cooperating ratchet ring, keys on said ratchet ring engageable with keyways on the drill to hold said ratchet ring against rotation, means for guiding said ratchet ring for axial movement, pawl engaging and releasing means movable axially with said ratchet ring into pawl engaging and releasing position to release entirely the pawls from engagement with the teeth of said ratchet ring, and means for actuating said ratchet ring in either direction by fluid pressure including a piston secured to said ratchet ring and means for supplying fluid pressure to act on said piston. 10
9. In a rock drill, drill steel rotation means including an oscillatory pawl carrier and a cooperating ratchet ring, operative connections between the pawl carrier and a drill steel to be rotated, means for holding said ratchet ring against rotation including members formed on said ratchet ring having interlocking engagement with members formed on a relatively stationary part of the drill, means for effecting axial movement of said ratchet ring, and means movable axially with said ratchet ring for engaging the pawls of said pawl carrier for releasing the pawls entirely from the teeth of the ratchet ring. 15
10. In a rock drill, drill steel rotation means including an oscillatory pawl carrier and a cooperating ratchet ring, operative connections between the pawl carrier and a drill steel to be rotated, means for holding said ratchet ring against rotation including members formed on said ratchet ring having interlocking engagement with members formed on a relatively stationary part of the drill, means for effecting axial movement of said ratchet ring, and means movable axially with said ratchet ring for engaging the pawls of said pawl carrier for releasing the pawls entirely from the teeth of the ratchet ring, said ratchet ring being movable axially into pawl releasing position while said interlocking members remain in interlocking engagement. 20
11. In a rock drill, drill steel rotation means including an oscillatory pawl carrier and a cooperating ratchet ring, operative connections between the pawl carrier and a drill steel to be rotated, means for holding the ratchet ring against rotation including members formed on the ratchet ring having interlocking engagement with members on a relatively stationary part of the drill, means for axially moving said ratchet ring, and pawl release means movable axially with said ratchet ring for effecting release of the pawls of 25
- the pawl carrier from the teeth of the ratchet ring, said ratchet ring being movable axially to move said release means into its pawl releasing position while said interlocking members remain in interlocking engagement. 5
12. In a rock drill, drill steel rotation means including relatively rotatable ratchet and pawl carrier elements, the ratchet element having ratchet teeth with which the pawls of said pawl carrier element cooperate, means for holding said ratchet element against rotation and for guiding said ratchet element for axial movement, pawl release means movable axially with said ratchet element and engaging with the pawls of said pawl carrier element for entirely releasing the pawls from engagement with the ratchet teeth, and means for moving said ratchet element axially. 10
13. In a rock drill, drill steel rotation means including relatively rotatable ratchet and pawl carrier elements, the ratchet element having ratchet teeth with which the pawls of said pawl carrier element cooperate, means for holding said ratchet element against rotation and for guiding said ratchet element for axial movement, pawl release means movable axially with said ratchet element and engaging with the pawls of said pawl carrier element for entirely releasing the pawls from engagement with the ratchet teeth, and means for moving said ratchet element axially. 15
14. In a rock drill, drill steel rotation mechanism including relatively rotatable ratchet and pawl carrier elements, the ratchet element having ratchet teeth with which the pawls of the pawl carrier element are adapted to cooperate and movable into rotation permitting and rotation interrupting positions, means for interlocking said ratchet element with a relatively stationary part of the drill for holding said ratchet element against rotation when in either of its respective rotation permitting or interrupting positions, with respect to the pawl carrier element, means for axially guiding said ratchet element during movement thereof into its different operative positions aforesaid, means movable axially with said ratchet element and engageable with the pawls of said pawl carrier element in one of said positions but not the other for entirely releasing the pawls from the ratchet teeth, and means for effecting relative axial movement between said elements. 20
15. In a rock drill, drill steel rotation mechanism including an oscillatory pawl carrier member and a cooperating ratchet ring, means on the ratchet ring engageable with means on the drill for holding the ratchet ring stationary as regards rotation while permitting axial movement of the ratchet ring, means for effecting axial movement of the ratchet ring, and pawl release means movable axially with said ratchet ring into a position to effect complete release of the pawls from the ratchet teeth while said holding means on the ratchet ring remain in engagement with the holding means of the drill. 25
